Inventor
Thornton A. Shinn,
by his attorney John C. Foster,

UNITED STATES PATENT OFFICE.

THORNTON A. SHINN, OF COOLBAUGH'S, PENNSYLVANIA.

DESIGN FOR A CHAIN-LINK.

SPECIFICATION forming part of Design No. 17,378, dated June 7, 1887.

Application filed April 29, 1887. Serial No. 236,599. Term of patent 14 years.

To all whom it may concern:

Be it known that I, THORNTON A. SHINN, a citizen of the United States, residing at Coolbaugh's, in the county of Monroe and State of Pennsylvania, have invented and produced a new and original Design for Chain-Links; and I do hereby declare the following to be a full, clear, and exact description of the invention, such as will enable others skilled in the art to

10 which it appertains to make and use the same. The design relates to a link for chains; and it consists of a link distinguished by its peculiar shape, which will be hereinafter set forth and claimed.

15 In the accompanying drawings, Figure 1 is a perspective view of the link. Fig. 2 is a bottom plan view of the same. Fig. 3 is a longitudinal section on line xx of Fig. 2. Fig. 4 is a top plan showing the link provided with 20 an ornamentation.

Like letters denote like parts.

My newly-designed chain-link has a section, A, of a general quadrangular contour, with one face sloping from edge to edge and the 25 other having a ridge, a , along one edge, broken at a point by an indentation, b . The link has also a skeleton quadrangular part, B, having an upturned longitudinal portion, c , at right

angles to the remainder of the part B. The parts A and B lie substantially in the same 30 plane alongside of and parallel to each other, and between them is the web D, located at a point about two-thirds of the distance lengthwise of the parts A and B.

The surface of part A may be provided with 35 ornamentation. (See Fig. 4.)

What I claim is—

1. The design for a chain-link, consisting of the quadrangular outline of one part having a ridge along one edge, the quadrangular skeleton upturned contour of the other portion, 40 and the web between the two parts, substantially as described and shown.

2. The design for a chain-link, consisting of the quadrangular outline of one part of the 45 link, with ornamentations thereon, the skeleton quadrangular upturned contour of the other portion, and the web between the two parts, substantially as described and shown.

In testimony whereof I affix my signature in 50 presence of two witnesses.

THORNTON A. SHINN.
